(57) **CLAIM**

The ornamental design for a front combination lamp for a
motor scooter, as shown and described.

DESCRIPTION

FIG. 1 is a perspective view from the front side of a front
combination lamp for a motor scooter.

FIG. 2 is a perspective view from the front side thereof.

FIG. 3 is a perspective view from the rear side thereof.

FIG. 4 is a perspective view from the rear side thereof.

FIG. 5 is a front elevation view thereof.

FIG. 6 is a rear elevation view thereof.

FIG. 7 is a right side elevation view thereof.

FIG. 8 is a left side elevation view thereof.

FIG. 9 is a top plan view thereof.

FIG. 10 is a bottom plan view thereof; and,

FIG. 11 is a referential view showing use thereof.

The portions of the front combination lamp shown in broken
lines are for the purpose of showing environmental structure
only and form no part of the claimed design.
